UNITED STATES PATENT OFFICE

OLOF R. OLSON, OF KANSAS CITY, MISSOURI

ATTACHMENT FOR CUTTING AND FLANGING MACHINES

Application filed April 29, 1929. Serial No. 359,000.

My invention relates to an attachment for cutting and flanging machines and my object is to provide a new and useful attachment of this character which may be employed to advantage in the production of elliptical or other irregular shaped sheet metal plates such as are used as heads on sheet metal drums and other containers of elliptical or other irregular cross sectional configuration.

10 In carrying out my invention I employ means for supporting a sheet metal blank, and mechanism for guiding said supporting means in such relation to the cutting and flanging mechanism that said blank will be 15 accurately cut in the desired shape and have a marginal flange formed thereon.

In the accompanying drawings which illustrate one form of the invention:

Fig. 1 is a fragmentary side elevation of a 20 cutting and flanging machine provided with my attachment.

Fig. 2 is a plan view of the attachment removed from the cutting and flanging machine.

25 Fig. 3 is an enlarged plan view of a guide and a support therefor forming parts of my attachment.

Fig. 4 is a broken sectional view on line 4—4 of Fig. 3 with the addition of a rotary table 30 which is operably mounted upon the guide.

Referring in detail to the various parts disclosed by the drawings, 2 designates a portion of the cutting and flanging machine which is provided with rotary cutters, not shown, and 35 a flanging roller 4, which latter is fixedly mounted upon a driven shaft 6. The shaft 6 is pivotally mounted at its driven end, not shown, so that it may be swung up or down to position the roller 4 upon the sheet metal 40 blank A for the purpose of forming a marginal flange thereon after said blank has been cut into proper shape by the cutting rolls. As the cutting and flanging machine may be of any well-known type, a detail description 45 thereof is deemed unnecessary.

Referring now more particularly to the parts constituting the present invention, 8 designates a bed which is bolted or otherwise firmly secured to the front side of the cutting 50 and flanging machine 2.

10 designates movable supporting means provided at its under side with slides 12 and 14 which operate upon a way 16 at the upper portion of the bed 8. The slide 12 is provided with a depending nut 18 which is 55 threaded upon a horizontally disposed screw 20 journaled in suitable bearings 22 formed in the bed 8. The screw 20 may be rotated to move the slides 12 and 14 and the parts carried thereby into or away from the cutting 60 and flanging machine by means of gears 24 and 26 and a hand wheel 28.

The supporting means 10 consists preferably of a channel bar bent midway between its ends into U-form as shown more clearly by 65 Figs. 1 and 3, around the lower end of the post 30 of a swingable crane carried by said supporting means 10. The post 30 is provided at its upper and lower portions with anti-friction bearings 32 upon which a tubular 70 shaft 34 is journaled. The top of the hollow post 30 is closed with a cap 46.

The tubular shaft 34 is provided with a horizontally disposed arm 38 which may be swung in a circle and is preferably of hollow 75 rectangular shape in cross section and provided with guide rollers 40 between which a carriage 42 is arranged to travel back and forth in said arm 38. The carriage 42 consists of a body 44 and rollers 46 upon which 80 latter said body 44 is mounted. The forward end of the body 44 is internally threaded for the reception of a vertically disposed screw 48 extending through slots 50 in the upper and lower sides of the arm 38. 85

The screw 48 is provided at its upper end with a hand wheel 52 and has an antifrictional universal connection 54 at its lower end with a rotary clamp 56. The clamp is adapted to firmly hold the sheet metal blank 90 A upon a rotatable table 58, which is mounted upon antifriction bearings 60 carried by a guide member 62 firmly secured by suitable means such as screws 64 to the upper portion of the adjustable supporting member 10. The rotatable table 58 is equipped with a peripheral rim 64^a which is of elliptical or the same contour as the finished sheet metal head is to be. The rim 64^a is removably secured to the table 58 by suitable 95 100

means such as screws 66 so that thicker or thinner rims may be substituted when larger or smaller sheet metal heads are to be produced from the blanks A.

5 The movements of the rotatable table 58 are directed upon the guide member 62 by suitable means such as rollers 68, 70, 72, 74 and 76 which travel in grooves 78, 80, 82, 84, 86, 88, 90 and 92 formed in the upper portion of said guide member 62. The rollers 68, 70, 72, 74 and 76 are mounted upon stub shafts 94 depending from the rotatable table 58. In the present instance the grooves 78 and 86 form an approximate ellipse as do 10 likewise the grooves 82 and 84, while the groove 80 and 88 parallel the grooves 78 and 86, respectively.

20 96 designates a thrust roller engaging the under side of the rotatable table 58 and the inner surface of a depending rail 98 extending around the margin of said table 58. As shown by Fig. 1 the thrust roller 96 is arranged near the flanging roller 4 for the purpose of preventing the table 58 from being 25 forced backwardly by said flanging roller 4 and thus causing undue pressure upon the stub shafts 94 and the rollers carried thereby. The thrust roller 96 is mounted upon a stub shaft 100 carried by a bracket 102 bolted 30 or otherwise firmly secured to the forward ends of the supporting means 10.

35 In practice a sheet metal blank, such as A, to be cut and flanged is firmly secured upon the table 58 by means of the clamp 56 which is forced downwardly upon said blank by means of the screw 48. The machine 2 is equipped with the cutting rolls, not shown, after which the supporting means 10 and parts carried thereby are adjusted towards 40 the machine 2 by turning the hand wheel 28 in order to bring the blank sheet A into proper position to be trimmed. The rotary cutters are then set in motion for the purpose of rotating and cutting the sheet A, the shape 45 of which latter is controlled by the grooves in the guide member 62 and the rollers 68, 70, 72, 74 and 76.

50 It is immaterial whether the cutting rollers when operating on the blank A drive the table 58 in a clockwise or anticlockwise direction, but assuming that the table is driven in a clockwise direction, the operation is as follows: When the roller 72 reaches the center of the groove 86 as shown by Fig. 3, it is held 55 stationary by the rollers 68, 70, 74 and 76 as they travel to the right in the respective grooves 78, 90, 80 and 92, as indicated by the arrows. When the roller 72 is held stationary as stated, it becomes the center of a short 60 arc described by the front end of the table 58 and on which one end of the blank A is cut to form one end of the oval head as shown at the left end of Fig. 2. The roller 72 remains stationary while the roller 68 travels 65 from the left to the right end of the groove 78,

at which time the roller 70 reaches the center of the groove 80 where it is held stationary by the other rollers and forms the center of a long arc on which one of the long sides of the blank A is cut as shown by dotted lines 70 at the left end of Fig. 2. The roller 70 remains stationary until the roller 68 reaches the center of the groove 86 where it is held stationary by the other rollers and constitutes the center of a short arc equal to the first-mentioned short arc and on which the opposite end of the blank is cut. The roller 68 remains stationary until the roller 74 reaches the center of the groove 80 after traveling through the grooves 92, 88 and 90. On reaching the center of the groove 80, the roller 74 is held stationary by the other rollers and constitutes the center of a long arc equal to the first-mentioned long arc and on which the opposite long side of the blank 80 is cut to complete the cutting of said blank. After the blank A has been cut into oval shape the rotary cutters are either removed or swung out of the way while the flanging roller 4 is brought into position and gradually 90 moved downwardly to the dotted line position, Fig. 1, to form the flange of the head as the table 58 is turned another revolution in the same manner as when the blank A was being cut into oval shape. During the cutting and flanging operations the arm 38 of the crane swings laterally and the carriage 42 moves to and fro as the table 58 gyrates, while the roller 76, which is positioned in axial alignment with the screw 48, traverses 95 the grooves 82 and 84 and cooperates with the rollers 68, 70, 74, 76 and 96 and the grooves 78, 90, 80, 92 and 88 in maintaining a uniform distance between the cutting and flanging rollers and the adjacent margin of 100 the table 58.

105 In practice the shape and length of the grooves in the guide member 62 may be varied according to the shape and size of the sheet metal head desired. I also reserve the right to make such other changes and modifications as properly fall within the spirit and scope of the invention.

110 Having thus described my invention, what I claim and desire to secure by Letters Patent is:

1. An attachment for sheet metal blank cutting and flanging machines consisting of a rotatable table for supporting and guiding sheet metal blanks while being cut and flanged, a guide member upon which said table is operably mounted, said guide member having grooves for determining the shape in which the blanks are to be cut, rollers on the table and arranged to travel 120 in said grooves and cooperate therewith in determining the shape in which the blanks are to be cut, and means for securing the blanks upon said table.

2. An attachment for sheet metal blank 125

- cutting and flanging machines consisting of a rotatable table for supporting and guiding sheet metal blanks while being cut and flanged, a guide member having ball bearings upon which said table is operably mounted, said guide member also having approximately elliptical shaped grooves and other grooves paralleling the aforementioned grooves and cooperating therewith in determining the shape in which the blanks are to be cut, means depending from the table into said grooves for cooperating therewith in determining the shape of the blanks, means for securing the blanks upon said table, and swingable means for carrying said securing means.
3. An attachment for sheet metal blank cutting and flanging machines consisting of a rotatable table for supporting and guiding sheet metal blanks while being cut and flanged, guide means for said table for determining the shape in which said blanks are to be cut, clamp means for securing the blanks upon said table, a thrust roller for preventing the table from being forced backwardly by the cutting and flanging mechanism, and a swingable crane carrying said blank securing means.
4. An attachment for sheet metal blank cutting and flanging machines consisting of a bed, supporting means slidably mounted upon said bed so that said supporting means may be adjusted towards or away from the cutting and flanging mechanism, a rotatable table for supporting and guiding sheet metal blanks while being cut and flanged, guide means for said table mounted on the supporting means for determining the shape in which the blanks are to be cut, clamp means for securing the blanks upon said table, screw means for adjusting said clamp means in and out of engagement with the blanks, a carriage in which said screw means is adjustably mounted, an arm in which said carriage is adapted to travel, a tubular shaft carrying said arm, and a post fixed to the supporting means and upon which said tubular shaft is journaled.
5. An attachment for sheet metal blank cutting and flanging machines consisting of a bed, supporting means slidably mounted upon said bed so that said supporting means may be adjusted towards or away from the cutting and flanging mechanism, mechanism for sliding said supporting means upon the bed, a rotatable table for supporting and guiding sheet metal blanks while being cut and flanged, guide means for said table mounted on the supporting means for determining the shape in which the blanks are to be cut, clamp means for securing the blanks upon said table, screw means for adjusting said clamp means in and out of engagement with the blanks, a carriage in which said screw means is adjustably mounted, an arm in which said carriage is adapted to travel, a tubular shaft carrying said arm, and a post fixed to the supporting means and upon which said tubular shaft is journaled.
- in which said carriage is adapted to travel, a tubular shaft carrying said arm, and a post fixed to the supporting means and upon which said tubular shaft is journaled.
6. A machine of the character described consisting of a rotatable table for supporting and guiding blank sheets while being cut, guide means for said table for determining the shape in which said blanks are to be cut, means for securing the blanks upon said table, a reciprocatory carriage supporting said blank securing means, a swingable arm supporting said carriage upon the table, a tubular shaft upon which said arm is fixed, and a vertically disposed post upon which said shaft is journaled.
7. In a machine of the character described, rotary means for supporting and guiding blank sheets while being cut, supporting means for said rotary means, approximately elliptical-shaped grooves and other grooves in one of said supporting means, and means on the other supporting means for traveling in said grooves and cooperating with the latter in guiding the blank supporting means.
- In testimony whereof I affix my signature.
- OLOF R. OLSON.
